His Attorney.

UNITED STATES PATENT OFFICE.

WINFIELD A. ATWOOD, OF SCHENECTADY, NEW YORK, ASSIGNOR TO GENERAL ELECTRIC COMPANY, A CORPORATION OF NEW YORK.

ELECTRIC SWITCH.

1,323,810.

Specification of Letters Patent.

Patented Dec. 2, 1919.

Application filed December 30, 1918. Serial No. 268,853.

To all whom it may concern:

Be it known that I, WINFIELD A. ATWOOD, a citizen of the United States, residing at Schenectady, in the county of Schenectady, 5 State of New York, have invented certain new and useful Improvements in Electric Switches, of which the following is a specification.

My invention relates to electric switches 10 and particularly to circuit breakers and has for its object to provide a circuit interrupting device which is held latched in circuit closing position and cannot be unlatched by excessive vibrations or jarring of the device.

15 Circuit breakers heretofore known in the art have been held closed by a form of latching means which, when subjected to jars and vibrations, have been readily moved to release the circuit breaker and permit it to 20 open. Particular instances of such excessive jars or shocks may be mentioned those occurring on battleships, cruisers and like war craft when firing heavy guns and especially broadsides. Circuit breakers heretofore 25 known in the art used under such circumstances have opened under the jars of cannonading and the opening of the breakers controlling the lighting, power and signal circuits has severely crippled service and 30 rendered the breakers unfit for such uses. The novel and improved form of circuit breaker embodying my invention overcomes the apparent limitations of circuit breakers heretofore known and comprises a latching 35 means which cannot be readily unlatched by jars and which is adapted to be held in latching position by an auxiliary latching or locking means.

40 The novel features which I believe to be characteristic of my invention will be definitely indicated in the claims appended hereto, while the features of construction and mode of operation will be understood by reference to the following description taken 45 in connection with the accompanying drawing, which shows the preferred embodiment of my invention and in which:—

Figure 1 is a side elevation of a circuit breaker embodying my invention having a 50 portion removed for clearness; Fig. 2 is a front view of a portion of the circuit breaker shown in Fig. 1; Fig. 3 is a top view of the latching means shown in Figs. 1 and 2; and Fig. 4 is a side view of a portion of a circuit

breaker embodying a simplified form of my 55 invention.

As shown in Fig. 1, the circuit breaker comprises stationary, main contacts 1 and 2 with which a movable current carrying member 3 coöperates to control the circuit 60 through the breaker. As is usual on such devices, the breaker is also provided with co-operating, secondary and tertiary contacts 4 and 5 respectively, to prevent burning the main contacts and take the arc as the breaker 65 opens. The circuit breaker is also provided with an operating member 6 which controls the current carrying member 3 through a suitable mechanism 7.

For restraining the circuit breaker in circuit closing position, I provide a latching means which comprises a pivotally supported member or arm 8 preferably pivoted to the member 9 supporting the current carrying member 3. Pivotally carried by the arm 70 8 and preferably at one end thereof, is a latching member or dog 10 biased by means of a gravity or a spring, not shown, to latching position. The member 10 coöperates to restrain the operating member 6 in circuit 75 closing position by engagement with a depending portion 11 carried by the operating member 6 and having a latching recess therein. The arm 8 and latching member 10 are so arranged that in restraining position 80 the point of engagement of the member 10 in the latching recess of the portion 11 of the operating member, is below a line through the pivotal connections of the members 8 and 10, and the member 10 is biased in 85 this position affording an underset latching means. To limit the movement of the members 8 and 10 in underset position a stop 10^a 90 is provided against which the member 10 rests.

Coöperating with the latching means is a tripping or releasing means including an armature or tripping member 12 movable into tripping position either by hand or automatically in response to predetermined 100 abnormal conditions in the circuit of the breaker. For automatic operation, an electroresponsive device is provided operatively related to the armature 12, such a device being shown as a magnetic yoke 13 operatively 105 related to one terminal or stud of the breaker as is well known in the art.

The arm 8 has a tail portion 14 which ex-

tends into the path of movement of the armature or tripping member 12 so that as the member 12 is moved to tripping position, the arm 8 is moved about its pivot in such a 5 manner as to rock the latch 10 about its pivot until its point of engagement with portion 11 of the operating member moves above the line through the pivots of arm 8 and latch 10 to an overset position where- 10 upon the latching means releases the operating member 6 to permit the breaker to open.

As shown in Fig. 4, the latching means, as described, will withstand ordinary jars and shocks without releasing the operating mem- 15 ber as the shock must be great enough to move the operating member 6 against the spring pressure exerted by current carrying member 3 and to move the latch 10 under the bias of its spring above the line through the 20 pivots of arm 8 and latch 10.

To prevent the movement of latching means, as described, under abnormal shocks or jars, I provide a locking means for the latching means which restrains the latching 25 means and holds it inoperative until the occurrence of certain conditions. For this purpose, the latching member 10 is provided with an offset and downwardly extending portion or finger 15 preferably integral 30 therewith. Coöperating with the portion 15 is a pivotally supported locking member or arm 16 carried by the support 9 and preferably on a common pivot with the arm 8 and adjacent thereto, as best shown in Fig. 35. The locking arm 16 has, at one end, a latching recess 17 adapted to engage the finger 15 of the latch 10 and lock the latching means in latching position and hold the same inoperative. The other end of arm 16 40 terminates in a tail portion 18 which also extends into the path of movement of tripping member 12 but is arranged to extend below the portion 14 of arm 8 in a position to be engaged by the member 12 just prior 45 to its engagement with arm 8.

As shown in Fig. 1, the latching means is held positively locked and inoperative in circuit closing position by the locking means comprising the finger 15 and locking arm 50 16. Upon movement of the tripping member 12 to tripping position, the portion 18 of locking member 16 is first engaged which causes the member 16 to move out of engagement with the finger 15 of the latch 55 10 and into unlocking position. The latching means is now free of restraint so that the subsequent engagement of the armature with the tail 14 of arm 8 causes the release of the latching means as before described. 60 By the use of this locking arrangement, the latching means is held locked against movement so that any excessive shocks or jar- ring of the circuit breaker can not release the latching means.

65 In accordance with the provisions of the

patent statutes, I have described the principle of operation of my invention, together with the apparatus which I now consider to represent the best embodiment thereof; but I desire to have it understood that the 70 apparatus shown is only illustrative, and that the invention can be carried out by other means.

What I claim as new and desire to secure by Letters Patent of the United States, is:— 75

1. In a circuit breaker, the combination with a movable current carrying member of an operating member therefor, latching means coöperating with said member to restrain said breaker in circuit closing position, means unaffected by jars or vibrations of said breaker for locking said latching means in latching position, and means for first moving said locking means to unlock- 80 ing position and then moving said latching means to releasing position.

2. In a circuit interrupter, the combina- 90 tion with a movable current carrying member, of an operating member therefor, latching means for said operating member, comprising an arm, and a latching member pivotally mounted on said arm biased to latch- 95 ing position, and means carried by said operating member coöperating with said latching member to hold said operating member in switch closing position.

3. In a circuit breaker, the combination with a movable current carrying member, of an operating member therefor, and latching means for said operating member comprising a pivotally supported arm, a latching member pivotally supported at one end of said arm biased to latching position and coöperating with said operating member to restrain said member in circuit closing position, and means coöperating with the other end of said arm to cause said arm to move said latching member into releasing position. 100

4. In a circuit breaker, the combination with a movable current carrying member, of an operating member therefor, and latching means for said operating member comprising a pivotally supported arm, a latching member pivotally carried by said arm and biased to coöperate with said operating member so that the point of engagement therewith is below a line through the pivots of said arm and said latching member whereby said operating member is held in 110 circuit closing position, and means coöperating with said arm to cause said point of engagement to move above the line through said points whereby said latching member releases said operating member. 115

5. In a circuit breaker, the combination with a movable current carrying member, of an operating member therefor, a latch en- 120 gaging means carried by said operating member, and latching means comprising a 130

- pivotedly supported arm, a dog pivotedly supported on said arm coöperating with said latch engaging means to retain said operating member in circuit closing position, said dog being biased to coöperate with said arm to form an underset toggle, and means coöperating with said arm for moving said toggle to an overset position whereby the operating member is released.
10. In a circuit breaker, the combination with a current carrying member, of an operating member therefor, and latching means for said operating member comprising a pivotally mounted arm, a latching member pivotally carried by said arm and coöperating with said operating member to restrain said member in circuit closing position, means coöperating with said arm to move said latching member to releasing position, and locking means for holding said latching member in latching position until operated in response to said means.
15. In a circuit breaker, the combination with a current carrying member, of an operating member therefor, and latching means for said operating member comprising a pivotally mounted arm; a latching member pivotally carried by said arm in position to coöperate with said operating member and restrain said member in circuit closing position, said member being biased to restraining position, and means for preventing the movement of said latching means to releasing position by shocks or jars of said breaker.
20. In a circuit breaker, the combination with a current carrying member, of an operating member therefor, latching means for restraining said operating member in circuit closing position, locking means for holding said latching means in latching position irrespective of vibrations of said breaker, and means coöperating with said latching and locking means to cause the release of said operating member.
25. In a circuit breaker, the combination with a current carrying member, of an operating member therefor, latching means for restraining said operating member in circuit closing position comprising a pivotally supported arm, a latching member pivotally carried by said arm and coöperating with said operating member to hold said member in circuit closing position, a finger carried by said latching member, and a second pivotally supported arm coöperating with said finger to prevent the movement of said latching member to releasing position.
30. In a circuit breaker, the combination with a current carrying member, of an operating member therefor, a pivotally supported arm, a latching member pivotally carried by said arm and coöperating with said operating member to hold said member in circuit closing position, and means unaffected by vibrations of said breaker for locking said latching member in latching position.
35. In a circuit breaker, the combination with a current carrying member, of an operating member therefor, a pivotally supported arm, a latching member pivotally carried by said arm adapted to engage and restrain said operating member in circuit closing position, said latching member being biased to restraining position and having a depending portion, a second pivotally mounted arm engageable with said depending portion of said latching member to lock said member in latching position, and releasing means operative to first move said second arm to unlocking position and then move said first mentioned arm into position to release said latching member.
40. In a circuit breaker, the combination with a current carrying member, of an operating member therefor, latching means for restraining said operating member in circuit closing position, and means coöperating with said latching means to render said latching means unaffected by vibrations of said breaker.
45. In a circuit breaker, the combination with a movable current carrying member, of an operating member therefor, latching means for restraining said operating member in circuit closing position comprising a pivotally supported arm, a latching member pivotally carried by said arm and coöperating with said operating member to hold said member in circuit closing position, locking means to releasing position, and releasing means operative to first move said locking means to unlocking position and then move said latching means to releasing position.
50. In a circuit breaker, the combination with a movable current carrying member, of an operating member therefor, latching means for restraining said operating member in circuit closing position, locking means for preventing the movement of said latching means to releasing position, and releasing means operative to first move said locking means to unlocking position and then move said latching means to releasing position.
55. In witness whereof, I have hereunto set my hand this 28th day of December, 1918.
- WINFIELD A. ATWOOD.
